UNITED STATES PATENT OFFICE.

IRA H. McARTHUR AND ALONZO J. CARTER, OF MERIDIAN, MISSISSIPPI.

RAILWAY-CAR BRAKE.

1,126,802.

Specification of Letters Patent.

Patented Feb. 2, 1915.

Application filed November 7, 1914. Serial No. 870,866.

To all whom it may concern:

Be it known that we, IRA H. McARTHUR and ALONZO J. CARTER, both citizens of the United States, and both residing in Meridian, in the county of Lauderdale and State of Mississippi, have invented certain new and useful Improvements in Railway-Car Brakes, of which the following is a specification.

- 10 This invention relates to railway car brakes of the general kind in which the brake shoes are connected by brake beams, in turn connected to equalizing levers which are joined to each other by brake rods.
- 15 The object of this invention is to provide improved means for connecting the brake rods to the equalizing levers in such manner that they may be easily disconnected therefrom and moved out of the way in order
- 20 that the wheels and axles may be removed from the truck whenever desired, and with great facility without disturbing other parts of the truck.

Our improvements are illustrated in the accompanying drawings, in which—

- Figure 1 is a plan view of a car truck with our invention applied. Fig. 2 is a view on an enlarged scale and in transverse section of one of our improved brake rod slides. Fig. 3 is a perspective view of the slide. Fig. 4 is a detail view in section, showing the manner of applying the slide to an equalizing lever, and showing also its relation to other parts of the brake mechanism. Fig. 5 is a perspective view of the upper part of the slide. Fig. 6 is a perspective view of the lower part thereof.

The car truck shown is of a well known type.

- 40 A indicates the wheels, A' the axles, B the brake shoes, b their hangers C the brake beams, and D the equalizing levers. Each brake rod E is connected at one end e to an equalizing lever in any desired way. The 45 opposite end of each brake rod is connected with an equalizing lever by our improved brake rod slide, which comprises a lower member G, and an upper member H. The

lower member comprises a bottom part or base g which rests on the equalizing lever D, 50 parallel vertical flanges g' having a space between them to receive the brake rod, and laterally projecting arms g² which are parallel with each other and spaced sufficiently far apart to receive corresponding flanged 55 parts of the upper member of the slide. Recesses or openings are formed at m to receive parts of the upper member in a manner hereinafter described.

The upper member H comprises a body 60 portion h having a longitudinal extension h' and formed with downwardly projecting flanges h² adapted to enter between the arms g² of the lower member in the manner shown in Fig. 3. The arms g² and the flanges h² 65 are perforated as indicated at g³ and h³ to receive the connecting pins N which are headed at n and at their opposite ends are provided with removable cotter-pins n'.

When the slide members are assembled 70 they are arranged as shown in Fig. 3, the flanges h² fitting between the arms g² within the recesses m. The brake rod extends through the slide between the flanges g' and is held in place by the nut e'.

75 The brake mechanism operates in the usual way, but should it be desired to remove the wheels and axles one of the pivot pins N of each slide should be removed and the top of each slide should be swung upward in the 80 manner indicated in Fig. 2. The brake rods may then be lifted clear of the axles and the latter with their wheels may be easily withdrawn.

We claim as our invention:—

1. A brake rod slide, comprising two members between which the rod is housed, means for pivotally connecting the members with each other on one side, and means for detachably connecting them on the other 90 side.

2. A brake rod slide, comprising two members between which the rod is housed, the lower part being formed with parallel flanges having a space between them to accommodate the rod and with parallel lat- 95

erally projecting arms, and the upper member being provided with a cover for the brake rod and with flanges arranged between the arms of the lower member, and pins connecting said flanges and arms, one of which pins acts as a pivot for the upper member of the slide and the other of which pins is removable for the purpose specified.

Copies of this patent may be obtained for five cents each, by addressing the "Commissioner of Patents, Washington, D. C."

In testimony whereof, we have hereunto subscribed our names.

I. H. MCARTHUR.
ALONZO J. CARTER.
